(57) **CLAIM**

The ornamental design for a dispensing cabinet, as shown and described.

DESCRIPTION

FIG. 1 is a front, top, perspective view of a dispensing cabinet showing my new design;

FIG. 2 is a front view thereof;

FIG. 3 is a left side view thereof, of which the right side is a mirror image; and,

FIG. 4 is a top view thereof.

The broken lines illustrate portions of the dispensing cabinet and form no part of the claimed design.
